CONTAINER AND CLOSURE THEREFOR

William Horlick, Jr., Racine, Wis.

Application November 17, 1932, Serial No. 642,997

1 Claim. (Cl. 220—42)

This invention relates to a container and closure therefor and has particular reference to containers in which a product may be stored for long periods of time and which containers may 5 subsequently be opened and the product dispensed from the container in small quantities over a comparatively short period of time.

The main object of the invention is to provide a container and closure therefor which will provide a practically impervious container for the product to facilitate storage thereof for an indefinite length of time; to provide a closure structure for such a container which may be opened to afford access to the contents of the 15 container and then be replaced so as to be freely removable from time to time while still providing an effective seal for the container.

Other objects and advantages of the invention will be understood by reference to the following specification and accompanying drawing in which there is illustrated a container and closure embodying a preferred form of the invention.

In the drawing:—

Figs. 1 and 2 are axial sections through a container. Fig. 3 is a fragmentary section similar to a portion of Fig. 1, but showing a slightly modified arrangement.

Referring now to the drawing, the container therein illustrated includes a body 5 having a bottom closure 6 secured thereto in any conventional manner. The container body 5 may be cylindrical, square or any other suitable shape or plan, and for the purpose of this application it may be assumed to be cylindrical.

35 The top of the container body is indicated at 7 and it is provided with a comparatively large mouth opening indicated at 8 which is surrounded by an upstanding flange 9 formed integral with the top piece 7. The flange 9 is preferably provided with an inwardly and downwardly rebent portion 10 so as to provide a smooth, non-cutting upper end or edge 11 on the upstanding mouth flange.

40 The closure for the mouth 8 is in the form of a cup-shaped member and it includes an end wall or closure 12 and a side portion 13. The side portion 13, adjacent its outer or open end, is enlarged as indicated at 14, a shoulder portion 15 serving to connect the adjacent ends of the outer or enlarged portion 14 and inner or smaller portion 15 of the said side 13.

45 As indicated in Fig. 1, the external diameter of the smaller or inner end portion 15 of the closure is such as to fit snugly in the flange opening 8 of the container. The fit may be a tight

frictional fit which effectively seals the container so as to form a substantially impervious receptacle for the storage of food stuffs or other products. A suitable washer or gasket may, if desired, be placed around the end portion 15 to further insure an impervious joint between the mouth flange and the cover, or a washer may be interposed between the shoulder 15 and the edge of the flange on which the shoulder 15 may seat. It will, of course, be understood that if desired, 10 the diameter of the cover portion 16 may be such that an effective seal is provided between the engaging faces of the cover portion 16 and mouth flange 9, before the shoulder portion 15 seats on the mouth flange. In that case, a slight space 15 will remain between the shoulder 15 and flange end which facilitates the insertion of a suitable tool for prying the cover out of the mouth. This arrangement is illustrated in Fig. 3.

Once the cover is removed from its initial position as indicated in Fig. 1, it may be replaced in the same position or, if it is desired to subsequently remove the cover at frequent intervals, it may be replaced in inverted position as illustrated in Fig. 2. For this purpose, the outer or 25 enlarged cover portion is formed of such internal diameter that it fits freely over the mouth flange 9 and yet tight enough to constitute a substantially dust and moisture proof closure for the container. When the cover is replaced in the 30 position shown in Fig. 2, the shoulder 15 is adapted to seat on the end of the mouth flange to improve the seal between the cover and mouth flange.

The above described container structure is 35 particularly adapted for holding malted milk powder and other products of this nature which are dispensed in small quantities at frequent intervals direct from the container in which furnished by the manufacturer.

Changes may be made in the described structure without departing from the spirit of the invention, the scope of which should be determined by reference to the following claim, the same being construed as broadly as possible, consistent 45 with the state of the art.

I claim as my invention:—

The combination of a container having a dispensing opening and an upstanding neck surrounding such opening, and a closure for said 50 opening comprising a deep, cup-shaped member including an end wall and a side wall, the transverse dimension of the closure being enlarged adjacent its outer or open end so as to provide inner and outer end portions of different sizes and a 55

5 shoulder connecting the adjacent ends of said inner and outer portions, the inner portion being of such size as to tightly but removably fit in said neck to provide a substantially air-tight seal for the container and the outer portion being of such size as to freely, removably fit over the outside of said neck, said shoulder being of relatively narrow width so that the said wall portion of the cover constituting said enlarged portion is not materially offset laterally from alignment with

said upstanding neck when said inner portion is seated in said neck, the depth of said outer portion being greater than the width of said shoulder, whereby the cover is adapted to withstand permanent deformation sufficient to impair its usefulness as a freely removable cover, by prying force applied to said shoulder to remove the cover from said tightly fitting position. 5
